SLEEPING BAG CARRIER

Wanda L. Hepper, Rte. 2, Meridian, Ohio 83642

Filed Feb. 25, 1970, Ser. No. 21,609

Term of patent 14 years

Int. Cl. D3—99

U.S. Cl. D87—1

FIG. 1 is a front perspective view of a sleeping bag carrier showing my new design in fully open condition and showing to advantage an inner surface including frictional material such as rubber or plastic "waffled" pattern adapted to frictionally hold contents and fabric material fastening means, indicated by partial shading, distally disposed near the opposite terminal edges thereof and adapted to form a closure means therefor;

FIG. 2 is a rear perspective view thereof showing a substantially smooth fabric outer covering which is substantially continuous over the outer surface thereof and indicated by partial shading;

FIG. 3 is a perspective view thereof in closed position.

I claim:

The ornamental design for a sleeping bag carrier, substantially as shown and described.
